TEMPERATURE REGULATION SYSTEM FOR
ELECTRIC DISCHARGE DEVICESHarry Kebbell Bourne, Rugby, England, assignor
to General Electric Company, a corporation of
New YorkApplication January 27, 1941, Serial No. 376,242
In Great Britain February 17, 1940

10 Claims. (Cl. 250—27.5)

My invention relates to the temperature regulation of electric discharge devices and more particularly to the temperature regulation of discharge lamps of the high pressure metal vapor type.

The current carrying capacity of an electric discharge lamp of the high pressure metal vapor type is limited by the operating temperature of the lamp envelope. If the temperature is too high it will cause deterioration of the refractory material of the bulb. If, however, the lamp is cooled by means of a blast of air or other cooling medium the temperature is lowered and consequently the capacity may be increased very considerably. It is possible by this means to make such lamps operate at very high wattages without a large increase in the size of the bulb. The reduction in bulb volume not only decreases the cost of the lamp but also the danger of explosion. At the higher wattages the luminous efficiency and the intrinsic brilliancy or intensity of the light source are also increased. Because of the greater light output and decreased size these sources become suitable for various projection applications.

However, in lamps as previously operated, that is in free air or with a simple cooling blast, the long delays before useful light output is obtained is a serious disadvantage for projection purposes. These delays resulted from: (1) the time taken for the lamp to reach its correct operating pressure and temperature after having been switched on in the cold state; and (2) the time taken for the lamp to cool down to allow restriking of the arc discharge if the lamp is extinguished for any reason, as a power failure, and is switched on when still hot.

It is an object of my invention to minimize these disadvantages by providing means whereby these times are very considerably reduced thereby to extend the field of application of the lamps. Further objects and advantages of my invention will appear from the following detailed description and drawings.

According to the invention I provide auxiliary heating means, an auxiliary directive cooling means and an auxiliary starting device. These and the main cooling means are operated in a predetermined sequence. A further cooling means may be employed, the function of which is to cool the seals. By this means very large currents may be carried through the seals whereby lamps of very high wattage may be made more easily.

The correct sequence of operating is as fol-

lows: On switching on from cold it is necessary to reach the desired operating temperature as quickly as possible. This is done by running the cold lamp with the auxiliary heater switched on and the cooling air turned off. When the lamp has reached a certain temperature, the heater is switched off and the cooling blast is turned on and the lamp will then continue to run up to its normal operating temperature corresponding to its normal operating wattage determined by the value of the impedance connected in series with the lamp. In the event of a failure of the mains supply followed by a restoration of the supply, a directive cooling means comes into operation, and this causes the mercury to condense rapidly at a point on the lamp bulb at which it can receive heat rapidly from the heater. The pressure in the lamp falls rapidly and when it is sufficiently low the lamp will restrike whereupon the cooling means are turned off and the heater is again switched on. The lamp then runs up rapidly to the value of the wattage at which the heater is switched off and the cooling blast is turned on.

25 The invention will now be described by reference to the accompanying drawing in which corresponding numerals indicate corresponding elements throughout and in which Fig. 1 is a

diagrammatic representation of the heating and cooling means of the present invention; Fig. 2 represents a circuit for operating said means; and Fig. 3 a modified form of the lamp of Fig. 1.

In Fig. 1 of the drawing a high pressure mercury vapor projection lamp 1 is mounted in such a way that it can be cooled by a main blast of air from a source 2. In order to remove the heat from the seals these are cooled by means of other air blasts from the jets 3—3. Underneath the lamp is mounted a heater 4 which is positioned so that the mercury in the lamp may be evaporated very rapidly. Through the center of this heater is projected an auxiliary air jet 5 by means of which a stream of air may be directed on to a spot on the bulb in order to condense the mercury rapidly when it is required to restrike the arc in the hot lamp. A Tesla coil 6 is connected to an auxiliary electrode in the lamp in order to reduce still further the striking time.

50 A circuit arrangement for operating this lamp is shown in Fig. 2. In this circuit the lamp 1 is supplied from the electrical mains 7—7 through the impedance 8 and the heater 4 which is connected in series with the lamp. In operating the lamp the air stream required for cooling

the seals is turned on and then the electrical supply to the lamp is switched on. The lamp then strikes and the lamp current which passes through the heater in series with the lamp heats it up and so evaporates the mercury rapidly, thus causing the lamp to approach its operating temperature and pressure quickly. When the lamp wattage has reached a certain value, the main cooling blast is turned on and at the same time the heater is short circuited. The lamp then continues to run-up to its normal operating wattage which is determined by the impedance in series with the lamp.

In the event of a momentary interruption in the mains supply, then the auxiliary air blast through the cooling jet 5 for condensing the mercury is turned on and the mercury is condensed very rapidly at the point in the bulb which is situated just above the heater 4. At the same time the Tesla coil 6 is switched on and after a short delay the lamp will restrike. After the arc restrikes the main and auxiliary cooling blasts at 2 and 5 are turned off while the heater 4 re-heats the lamp which runs up to normal operating temperature as before.

The various switching operations and the control of the air supplies may be carried out either manually or else automatically by means of relays as desired. For example, during the starting process, a relay 9 operated by thermostat 10 adjacent the lamp envelope may be arranged to deenergize heater 4 and initiate operation of main air blast 2 at any desired lamp temperature, preferably however at a temperature slightly below normal operating temperature. A relay 13 responsive to the high voltage existing across the lamp when it is out may prevent the deenergizing of air blast 2 and energization of heater 4 by relay 9 until the lamp has restarted, after having been deenergized while hot. Alternatively to 40 thermostat 10, a relay connected across the lamp and responsive to a voltage slightly lower than normal operating voltage may operate to deenergize the heater and turn on the main cooling blast as the lamp approaches operating temperature during the starting process. Another relay 12, responsive to the higher voltage existing across the lamp when it is out, may be used to start up the Tesla coil and to turn on the auxiliary air blast for cooling the lamp rapidly in the event of an interruption in the power supply. When the lamp restrikes, this relay will drop out as the voltage across the lamp will then become very low.

In order to reduce the heating-up time to a minimum it is necessary to supply heat to the mercury as rapidly as possible. This may be done by an external heater as described above, or by a heater which is actually enclosed within the lamp bulb itself. The gas used for starting in the lamp should give a high cathode drop in order to produce a high wattage in the lamp bulb, but this gas must not be such that a high starting voltage is required. The position and size of the jet used for the air for cooling a spot on the bulb to condense the mercury should be adjusted to condense the mercury as rapidly as possible, and also the position of this jet should be such that the mercury is condensed in a position on the bulb in which it will receive heat from the auxiliary heater as quickly as possible. By this means the time of restriking and the heating-up time will both be reduced.

Another form of lamp in which improved times for running up and for restriking may be obtained

is shown in Fig. 3. In this case the lamp 1 has on it an appendix 14 which contains the mercury. Around this appendix is placed a heater 4 which may be arranged to be in close contact with its surface, thus ensuring efficient heat transference. Also this appendix may be cooled by an air jet 5 very efficiently, and by this means the delay times for the lamp may be reduced even further.

It will generally be desirable to so shape and position the cooling and heating means of my invention as to provide a minimum interference with the emitted light of the lamp. Thus, for example, when the lamp is used in combination with a parabolic mirror for obtaining a light beam, it will be found advantageous to position the cooling or heating means or both directly between the rear of the lamp and the center of the mirror since light reflected from this portion usually returns to the lamp only to be intercepted by the lamp envelope and is, therefore, already useless for illumination purposes. Further the cooling pipes may be shaped with flattened cylindrical or elliptical cross-section and so oriented that minimum interference with the light results. Thus, where the lamp is positioned at the focus of a parabolic reflector, the supply pipes carrying the cooling fluid may be positioned either vertically in front of or behind the envelope and may terminate in a nozzle having an axis at right angles to the axis of the pipe. The nozzle may have an outwardly flared orifice directed toward the lamp envelope. The vertical portion of the pipe may be of elliptical cross-section with the major axis of the ellipse directed along the axis of the beam so that the pipe obstructs as little as possible the effective light emission.

It will be understood that the herein described arrangements are illustrative of but several forms of my invention and that numerous modifications and changes within the scope of the appended claims may occur to those skilled in the arts.

What I claim as new and desire to secure by Letters Patent of the United States is:

1. In combination with a high pressure vapor electrical discharge device comprising electrodes for sustaining a discharge and energizing means therefor, heating means, independent of said electrodes, to accelerate the approach of said device to its normal operating temperature, said heating means being energized upon starting of the device, and automatic means for deenergizing said heating means shortly before said device reaches said normal operating temperature and for thereafter maintaining said heating means deenergized during operation of the device.

2. In combination with a high pressure vapor electrical discharge device comprising electrodes for sustaining a discharge and energizing means therefor, cooling means, heating means, independent of said electrodes for accelerating the approach of said discharge device to normal operating temperature, said heating means being energized upon starting of the device, means for deenergizing said heating means shortly before said device reaches normal operating temperature and for thereafter maintaining said heating means deenergized during operation of the device, and means for initiating the operation of said cooling means only when said device approaches normal operating temperature and for continuing the operation of said cooling means throughout normal operation of the device.

3. In combination with a high pressure vapor electrical discharge device which is incapable of

being restarted at its normal operating temperature and pressure, and energizing means therefore, heating means for accelerating the approach of said device to normal operating temperature, said heating means being energized upon starting of the device, cooling means, means for deenergizing said heating means shortly before said device reaches its approximate normal operating temperature and for thereafter maintaining said heating means deenergized during operation of the device, means for initiating the operation of said cooling means only upon deenergization of said device after normal operation obtains, and means for deenergizing said cooling means when said device drops to a temperature permitting reenergization of said device.

4. In combination with a high pressure vapor electrical discharge device which is incapable of being restarted at its normal operating temperature and pressure, and energizing means therefore, localized heating means for accelerating the approach of said device to normal operating temperature, said heating means being energized upon starting of the device localized, cooling means in close proximity to said heating means, means for deenergizing said heating means shortly before said device reaches its approximate normal operating temperature and for thereafter maintaining said heating means deenergized during operation of the device, means for energizing said cooling means only upon deenergization of said device after normal operation obtains, and means for deenergizing said cooling means when said device drops to a temperature permitting reenergization thereof, the said cooling means being arranged to cool the same local portion of the device as is heated by said heating means.

5. In combination with a high pressure vapor electrical discharge device which is incapable of being restarted at its normal operating temperature and pressure, and energizing means therefore, heating means for accelerating the approach of said device to normal operating temperature, said heating means being energized upon starting of the device, primary and auxiliary cooling means, means for deenergizing said heating means shortly before said device reaches normal operating temperature and for initiating the operation of said primary cooling means thereafter throughout normal operation of the device, means for initiating the operation of said auxiliary cooling means only upon deenergization of said device after normal operation obtains and for deenergizing said auxiliary cooling means when the temperature of said device drops sufficiently to permit reenergization thereof, and means for deenergizing said primary cooling means until said device has reattained approximate normal operating temperature.

6. In combination with a high pressure vapor electrical discharge device which is incapable of being restarted at its normal operating temperature and pressure, and energizing means therefore, localized heating means for accelerating the approach of said device to normal operating temperature, said heating means being energized upon starting of the device, primary cooling means and auxiliary localized cooling means in close proximity to said heating means, means for deenergizing said heating means shortly before said device reaches normal operating temperature and for initiating the operation of said pri-

mary cooling means thereafter throughout normal operation of the device, means for initiating the operation of said auxiliary cooling means only upon deenergization of said device after normal operation obtains and for deenergizing said auxiliary cooling means when the temperature of said device drops sufficiently to permit reenergization thereof, and means for deenergizing said primary cooling means until said device has reattained approximate normal operating temperature, the said auxiliary cooling means being arranged to cool the same local portion of the device as is heated by said heating means.

7. In combination with a high pressure vapor electrical discharge device which is incapable of being restarted at its normal operating temperature and pressure, and energizing means therefore, heating means to accelerate the approach of said device to normal operating temperature, said heating means being energized upon starting of the device, air blasts comprising a primary cooling means and an auxiliary cooling means in close proximity to said heating means, means for deenergizing said heating means shortly before said device reaches normal operating temperature and for initiating the operation of said primary cooling means thereafter throughout normal operation of the device, means for initiating the operation of said auxiliary cooling means only upon deenergization of said device after normal operation obtains and for deenergizing said auxiliary cooling means when the temperature of said device drops sufficiently to permit reenergization thereof, and means for deenergizing said primary cooling means until said device has reattained approximate normal operating temperature.

8. The method of accelerating the restarting of a high pressure vapor electrical discharge device upon deenergization thereof after normal operation obtains which comprises applying additional cooling means thereto in addition to the normal cooling means until the temperature of said device drops sufficiently to permit reenergization thereof and thereafter discontinuing the normal cooling means until normal operation reoccurs.

9. The method of operating a high pressure vapor electrical discharge device which comprises supplying electrical energy to the device to initiate a discharge therein, simultaneously applying localized heat thereto in addition to that supplied by the discharge until the device approaches its normal operating temperature, applying cooling means at a point in close proximity to the point of application of said heat when said device is deenergized after normal operation obtains until the temperature of said device drops sufficiently to permit reenergization thereof.

10. The method of operating a high pressure vapor electrical discharge device which comprises supplying electrical energy to the device to initiate a discharge therein, simultaneously applying heat thereto in addition to that supplied by the discharge until the device approaches its normal operating temperature and applying to said device when said device is deenergized after normal operation obtains cooling means in addition to the normal cooling means until the temperature of said device drops sufficiently to permit reenergization thereof.

HARRY KEBBELL BOURNE.
